(57) **CLAIM**

The ornamental design for a metal tray, as shown and described.

DESCRIPTION

FIG. 1 is a horizontal, frontal view of the metal tray showing my new design with the handles straight vertical.

FIG. 2 is a diagonal, frontal view of the metal tray showing my new design with the handles diagonally-vertical; and, FIG. 3 is a diagonal, frontal view of the metal tray showing my new design with the handles flat horizontal.

The broken lines within the metal tray is for the purpose of illustrating context and form no part of the claimed design.
